UNITED STATES PATENT OFFICE.

HENRY MÜLLER, OF PHILADELPHIA, PENNSYLVANIA, ASSIGNOR OF ONE-HALF TO
JACOB BERNHARD, OF PHILADELPHIA, PENNSYLVANIA.

SANITARY GUARD FOR WATER-CLOSET SEATS.

1,158,142.

Specification of Letters Patent.

Patented Oct. 26, 1915.

Application filed February 26, 1915. Serial No. 10,672.

To all whom it may concern:

Be it known that I, HENRY MÜLLER, a citizen of the United States, residing in the city and county of Philadelphia, State of Pennsylvania, have invented a new and useful Sanitary Guard for Water-Closet Seats, of which the following is a specification.

My invention relates to a device adapted to be placed on the seat of a water closet bowl for guarding the body of the occupant of the seat from disease and filthiness that would be occasioned by and would exist on said seat.

To this end the invention consists in forming such device of a sheet or piece of paper and providing the same with a member that may constitute a tongue to be dropped into said bowl and adapting it to be extended so as to make said sheet or piece longer than the original length of the same, whereby said tongue may present an increased length of surface which is subjected to the action of the flush water thereon, whereby when the seat is unoccupied the entire device will be drawn down into the bowl and so disposed of through the soil pipe.

The invention is illustrated in the accompanying drawing, but the important instrumentalities thereof may be varied, as long as they are included in the scope of the claim.

Figure 1 represents a plan view of a sanitary guard for a water closet seat embodying my invention. Fig. 2 represents a vertical section thereof in operative condition in a bowl which also is in vertical section. Fig. 3 represents a vertical section on line α — α Fig. 2. Fig. 4 represents a top view thereof on a reduced scale. Fig. 5 represents a top view of a modification.

Similar numerals of reference indicate corresponding parts in the figures.

Referring to the drawings, 1 designates the guard the same being formed of a piece or sheet of paper or other suitable material in which is the longitudinally-extending tongue 2 which is formed by making incisions in the piece, in the present case, of the form of perforations on the lines 3 and 4, thus adapting the tongue to be separated to that extent from the piece leaving the end 5 of the tongue opposite to the incision 4 connected with said piece and comprising a hinge for the tongue by which it may drop from the portion of the piece or sheet at said

end 5. The portions of the piece or sheet 55 on the side of the tongue are cut through, in the present case, in the form of perforations on the lines 6 and 7, which form the supplemental tongues 8—8 which remain connected with the free end of the tongue 2 at the 60 places 9—9 which places constitute hinges for said tongues 8, whereby the latter may be turned outwardly from the sides of the free end of the tongues, as shown in dotted lines Fig. 1, by which provision the piece is 65 made of greater length than in its original condition.

When the rim 10 of the piece is placed on the rim of the seat, the tongues 2 and 8 are dropped into the bowl, when the tongue 70 2 will depend from the rim 10 and dip into the water and the tongues 8 will extend from the lower end of the tongue 2 in somewhat horizontal position so as to float on the sealing water usual in the bowl. The location 75 of the tongues provide the opening of the bowl, below the opening of the seat for the necessities of the case. As soon as the flushing is occasioned and the occupant of the seat rises the water of flushing carries with 80 it first the tongues 8. This drags the tongue with them and the latter drags the rim from the seat, and thus the entire device is pulled into the bowl and dashed out of the same with the water into the soil pipe, thus completely disposing of the device, it being evident that the tongues 8 in a flat or comparatively flat condition was subjected to the full power of the running water whereby the tongue 3 is caused to follow the same, and 90 with it the rim which was loose on the seat.

It is evident that sheets of the kind may be placed one on the other in bundles or inserted in a slot machine to be paid by a coin if so desired, so that when one sheet is in 95 hand the tongues may be pushed out of the sheet on the lines of the perforations unless previously full cut-through on said lines as in Fig. 5, where excepting the full or continuous cuts the construction of the members 100 is precisely the same as in the other figures, the perforations being preferred as the sheet is comparatively intact in normal condition, and so may be handled in a convenient manner located on the seat and punched-through 105 when the tongues as produced are dropped into the bowl with the effect hereinbefore stated.

Having thus described my invention what I claim as new and desire to secure by Letters Patent, is:—

In a sanitary guard for a water closet seat, 5 a piece of pliable material having an opening therein, a main tongue extending from the wall of said opening, and supplemental

tongues integral with opposite sides of the extremity of said main tongue to extend, in use, beyond the extremity of the latter.
